UNITED STATES PATENT OFFICE.

ALBERT J. HORTON, OF WHITE PLAINS, NEW YORK, ASSIGNOR TO THE CUTLER-HAMMER MFG. CO., OF MILWAUKEE, WISCONSIN, A CORPORATION OF WISCONSIN.

RESISTANCE.

1,293,440.

Specification of Letters Patent.

Patented Feb. 4, 1919.

Application filed May 24, 1916. Serial No. 99,451.

To all whom it may concern:

Be it known that I, ALBERT J. HORTON, a citizen of the United States, residing at White Plains, in the county of Westchester and State of New York, have invented new and useful Improvements in Resistances, of which the following is a full, clear, concise, and exact description, reference being had to the accompanying drawing, forming a part of this specification.

This invention relates to resistances and more particularly to those of the unit type.

The invention has among its objects to provide a simple, rugged and compact resistance device suitable for phonographs and other mechanisms.

Further objects are to provide a resistance unit with simplified terminal and supporting means and to provide for inclosure of a number of units in a compact and readily assembled structure.

Other objects will appear as the description proceeds.

In the drawing, wherein is illustrated an embodiment of the said invention,

Figure 1 is a top plan view of a resistance device constructed in accordance therewith;

Fig. 2 is an edge view, partly in section, of the resistance device illustrated in Fig. 1, while

Fig. 3 is an end view, partly in section, of the same.

Referring to Fig. 1, a plurality of resistance units 1 (in the present case 3) are terminally supported in parallel relation upon a flat base 2, said units being inclosed within a casing 3.

Referring more particularly to Figs. 2 and 3, each of the aforesaid units comprises a resistance wire 4 coiled about a bored cylindrical base 5 of porcelain or other non-conductive material, the respective ends of said resistance element being electrically connected with a pair of conductive bands 6-6 which surround said base adjacent to its opposite ends, said bands being preferably inset from the ends of the base as shown. In practice, the resistance element is surrounded by a cementitious covering extending between the bands 7.

Each of the bands 6 is bent to provide a pair of downwardly projecting lugs 8

which terminate in parallel overlapping portions 9 spaced from the periphery of the base 5. Each pair of projecting lugs 8 is provided with a clamping screw 10 for drawing the same together and thereby clamping the band firmly about the base 5. The parallel overlapping parts 9 of each band 6 are clamped together and in rigid engagement with a relatively heavy conductive strip 11 by rivets 12 passing through the aforementioned parts, whereby a strip 11 is attached to opposite ends of each unit. Each conductive strip 11 is provided with a downwardly bent portion 13 which portions serve as feet to support the resistance units and are at their outer ends clamped upon binding posts 14 which extend upward through the flat base 2 thus providing suitable line connections for the various units.

All of the resistance units being of similar construction, a plurality of the same may optionally be joined in series by means such as a connecting link 15 of Fig. 1, in which case the line connections are established through the unit terminals not otherwise engaged.

The casing 3 comprises a pair of flanged integral end pieces 16 and a single perforate front and side piece 17 shaped to fit about the requisite number of units 1 and within the flanges of the end pieces 16. The piece 17 also has its ends extended to the base 2 and there indent as shown in Fig. 3, while bolts 18 are passed through the bores of the resistance units 1 and through registering openings in the end pieces 16 of the casing, whereby the casing is supported by and firmly clamped upon the units. On the other hand, the casing being thus attached to the units serves to reinforce and rigidify the latter.

What I claim as new and desire to secure by Letters Patent is:

1. In a resistance device, the combination with a flat insulating base, of a resistance unit comprising an elongated insulating core and a resistance element surrounding the same, and combined terminal and supporting devices on opposite ends of said unit each including a part clamped about said core and electrically connected to said resistance element and a projecting part ar-

- 22
- ranged at substantially right angles to said former part and secured to the face of said base.
2. In a resistance device, the combination 5 with a flat insulating base, of a resistance unit comprising an elongated insulating core and a resistance element surrounding the same, combined terminal and supporting devices on opposite ends of said unit each including a part clamped about said core and electrically connected to said resistance element and a part arranged at substantially right angles to said former part and projecting beyond the end of said core and binding posts associated with the latter part of said devices serving to anchor the same to the face of said base.
3. A resistance unit comprising a base, a resistance element surrounding said base, 20 conductive bands surrounding said base near its opposite ends but inset therefrom, said bands being in electrical engagement with said resistance element and each being provided with downwardly projecting lugs and 25 overlapping sections spaced from said base, conductive strips riveted at their inner ends to the overlapping sections of said bands and having their outer ends bent to constitute supporting means for said unit, and 30 binding posts associated with said outer ends of said strips, said binding posts constituting anchoring means for said unit.
4. In a resistance device, the combination 35 with a flat insulating base, of a plurality of resistance units having individual terminal devices, said devices being secured to the face of said base to support their respective
- units, an inclosing casing for said units and means passing axially through said units to secure said casing thereto. 40
5. In a resistance device, in combination, a plurality of resistance units having individual conducting and supporting means, an inclosing casing for said units and means for supporting the same comprising bolts 45 passing axially through each said unit and through aligned openings in said casing.
6. In a resistance device, the combination 50 with a resistance unit comprising a cylindrical insulating base having a longitudinal bore, a resistance element surrounding said base, conductive clamping bands also surrounding said base and in contact with said resistance element, of a casing extending about said unit and secured thereto by a bolt passing through said bore, and supporting means for said unit and said casing including fixed conductive strips rigidly and electrically connected to said bands. 55
7. In a resistance device, the combination 60 with a plurality of resistance units each including a base, a resistance element and conductive clamping bands surrounding said base and contacting with said element, of a casing extending about said units and secured to certain of the same, and fixed conductive strips rigidly and electrically connected to said bands for supporting said units and said casing and providing electrical connections for the former. 65
- 70
- In witness whereof, I have hereunto subscribed my name.

ALBERT J. HORTON.
